CLAIM

The ornamental design for a housing for an electrical connector, as shown and described.

DESCRIPTION

FIG. 1 is a perspective view of a housing for an electrical connector showing my new design;

FIG. 2 is a top plan view thereof;

FIG. 3 is a front elevational view thereof;

FIG. 4 is a bottom plan view thereof;

FIG. 5 is a right side elevational view thereof, the left side elevational view being a mirror image;

FIG. 6 is a rear elevational view thereof;

FIG. 7 is a right side elevational view of a housing for an electrical connector showing my new design with the stopper plate open, the left side elevational view being a mirror image;

FIG. 8 is a rear elevational view thereof;

FIG. 9 is a cross-section view of a housing for an electrical connector showing my new design along line 9—9 of FIG. 3;

FIG. 10 is a cross-section view thereof along line 10—10 of FIG. 3.
